ORNAMENTAL CLASP

Christopher L. Migliaccio, Providence, R. I., assignor to Hingeco Vanities, Inc., Providence, R. I., a corporation of Rhode Island

Application June 20, 1940, Serial No. 341,485

2 Claims. (Cl. 24—49)

This invention relates to necktie or like clasps of personal wear, made of precious or other metal and often described as jewelry.

In the commercial production of such articles the ingenuity of the creator of any novel design is taxed to provide for a die production basis such that the finished article will expose a precious metal such as gold or silver and conceal the base metal backing which is commonly brass or like inexpensive alloy.

It is also much desired to have such clasps or other articles of personal wear simulate some well known article of purely utilitarian purpose so that its appearance in miniature produces a novel or amusing effect entirely consistent with its decorative and ornamental purpose.

In the present instance the immediate purpose is to provide a fastening or clasp of unique appearance which can be made of precious or other metal in commercial quantities at the minimum manufacturing cost.

In accomplishing this object, I deliberately have devised my clasp to simulate, in miniature, a common laundry clothespin which is novel and attractive when appearing as an article of jewelry.

As illustrative of my invention I have shown in the accompanying drawing a clasp of clothespin design capable of quantity production in plate or rolled stock at low cost but exhibiting a fine external finish comparable with jewelry of all precious metal composition.

Throughout the specification and drawing like reference characters are employed to indicate corresponding parts, and in the drawing:

Fig. 1 is a view indicating a necktie or like clasp of miniature clothespin design in accordance with my invention as worn with usual four-in-hand scarf.

Fig. 2 is a side elevation of such clasp.

Fig. 3 is a central longitudinal section through the clasp.

Fig. 4 is an interior view of one of the duplicate shells, before assembly.

Fig. 5 is an enlarged transverse section on the line 5—5 of Fig. 2.

Fig. 6 is an enlarged fragmentary section through the head of my clasp.

Fig. 7 is a view of the head button or stud before assembly, and

Fig. 8 is a view of the head cap shell, before assembly.

As the basic concept of my invention lies on the side of its manufacturing possibilities I will

discuss first its structural rather than its popular novelty aspects.

Referring to the sectional views based on Fig. 2 it will be seen that I have contrived to convert the rather crude old wooden clothespin models to artistic personal wear products of popular appeal. I have re-designed the old awkward wooden clothespin legs or fingers as sheet metal members of graceful configuration. These are in the form of duplicate shells, one of which is detailed in Fig. 4. Each shell comprises a concaved leg or finger portion 1' and a neck portion 2, conformable to the type of clothespin represented, be it round-turned, square, or otherwise worked out in the original wooden form from which the more precious metallized counterpart is to be styled.

In the form illustrated in the drawing each neck portion 2 is integral with the finger portion 1' and continues its concavity as a tapered or conic figure. At its upper end, each neck portion is formed with a semi-circular pocket-forming portion 3 which half-pockets when the duplicate shells are assembled define the hollow head of the clasp. Within the hollow clasp head I lodge a button-like filler 4 (see Fig. 7). The head of said filler 4 conforms to the internal shape of the clasp head, and the filler has a reduced neck 4' terminating in a shouldered disc 42 which bears against the interior walls of the neck portions 2 adjacent their juncture with the pocket forming portions 3. The concavity of the neck interior is continued to the interior of the clasp head as a circumferential groove or channel 5 adapted to receive the neck 4' of the filler 4.

The assembly is preferably completed by a head cap 6 (see Fig. 8) swaged over the exterior of the clasp head so as to anchor the filler 4 in position and to form a smooth tight external joint of the parts without the necessity of using solder. The parts could be soldered if desired, but the soldering of precious metal plate is apt to discolor the joint. By swaging the head cap 6 over the filler button 4, such button becomes in effect an end fulcrum contributing to the resilience of the fingers 1'. This gives to the finger pair a strong and positive clip action enabling them to secure a scarf or necktie T to a shirt front S as suggested in Fig. 1, although it will be understood that these little articles may be variously worn or used.

The semi-hollow or internally concaved fingers 1' receive the fabric of tie and shirt and so obtain a firm grip on it preventing slipping and so disarranging the tie or even resulting in the loss of the clasp itself. If desired the edges of the

5 fingers at their gripping zone may be given a slightly wavy or undulatory figure to increase the definiteness of its grip as suggested in Fig. 3 at 1^a. Being of metal they can have a smooth and rounded edge so as not to catch on threads or roughen the fabric surface.

As is well known to those familiar with this art it is usually desired to use so-called rolled plate on account of its inexpensiveness due to its 10 brass backing and the fine finishes which its gold or other precious metal surface will take and hold. The brass face of the stock being disposed towards the interior of the article is entirely unobjectionable and imparts the usual stiffness and strength 15 to the article without in any way interfering with the desired ductility in the dies or swages.

Various modifications in design and finish may and are intended to be made to suit different tastes. The configuration of parts and basis of 20 assembly may also be varied by those skilled in the art without departing from the essence of my invention as hereinafter claimed.

What I therefore claim and desire to secure by Letters Patent is:

25 1. In an ornamental clasp, a pair of oppositely assembled thin concavo-convex sheet metal members each including a shallow tapering finger portion and a half-round shoulder portion of

conic figure having at its end a semi-circular pocket, a solid button-like filler including a head flange of the size of the interior capacity of the pocket pair, a neck of a size filling the pocket and shoulder junction and a bottom flange disposed within the shoulders in supporting relation to the adjacent opposite shoulder pairs, and a head encirclement tightly holding said pocket portions on said filler as an end fulcrum for the finger portions whereby they are yieldably united as a unitary article. 5

2. In an ornamental clasp, a pair of oppositely faced thin sheet metal members each including a shallow finger portion and a half-round shoulder portion having at its end a semi-circular pocket, 10 a solid button-like filler including a head flange of the size of the pocket pair capacity, a neck disposed at the junction of said pocket and shoulder interiors and a bottom flange disposed within the shoulders in supporting relation to the adjacent 15 opposite shoulder pairs, said pocket portions being united over said filler as a head and said filler acting as an end fulcrum for the finger portions whereby they are yieldably united as a unitary article in semblance to a clothespin of laundry 20 25 type. 20
